RADIATOR

Martin I. Larsen, Chicago, Ill.

Application October 10, 1931, Serial No. 568,150

11 Claims. (Cl. 237—17)

This invention relates to heating apparatus, and more particularly to heating apparatus in the form of radiators provided with gas or other burners for heating water therein.

The invention has for one of its objects to provide a heating apparatus or radiator of the character stated which will embody a plurality of sections each having a water chamber, a combustion chamber located immediately below the water chamber and having horizontal dimensions similar to those of the water chamber, a flue in communication at one end with the combustion chamber and extending circuitously through the water chamber, and a burner element associated with the combustion chamber, to the end that all the heat generated by the burner may be utilized for the purpose of heating the water.

The invention has for a further object to provide a radiator of the character stated wherein the central section thereof will have an outlet orifice for connection with a chimney, wherein the flues of all the sections will communicate with said orifice at points remote from their points of communication with combustion chambers formed in the sections, and wherein the flues will be provided at points in their length with air inlet openings to insure a draft through the flues.

The invention has for a further object to provide a radiator of the character stated wherein the flue of each section will have an intermediate portion thereof located in the combustion chamber of the section directly above a portion of the burner element of the section, to the end that the products of combustion may be maintained at high temperature until discharged from the flue, and thus materially aid in utilizing substantially all the heat generated by the burner to raise the temperature of the water.

The invention has for a further object to provide a radiator of the character stated wherein the water compartments of the respective sections will be in communication, and wherein the central section will be provided with an expansion tank in communication with the water chamber of said section and provided with a filler plug and a water gauge.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a view partly in side elevation and partly in vertical section of a radiator constructed in accordance with my invention, the plane of the

section being indicated by the line 1—1 of Figure 2;

Figure 2 is a sectional view taken on a plane extending vertically and centrally through one of the end sections of the radiator, the plane of the section being indicated by the line 2—2 of Figure 1;

Figure 3 is a sectional view taken on a plane extending vertically and centrally through the central section of the radiator, the plane of the section being indicated by the line 3—3 of Figure 1;

Figure 4 is a sectional view taken on the planes indicated by the line 4—4 of Figure 2;

Figure 5 is a view in side elevation of a lower portion of one of the radiator sections illustrating one of the air inlet openings for the flues;

Figure 6 is a sectional view taken on the plane indicated by the line 6—6 of Figure 3, and

Figure 7 is a sectional view taken on the plane indicated by the line 7—7 of Figure 3.

The radiator which may be of any desired or required size, is shown for the purpose of illustration as embodying five sections or columns designated 1—5, respectively. The end sections 1 and 5 are provided with feet 6 and 7, respectively, to support the lower ends of the sections above the floor. The sections 1—5 are arranged in relatively spaced relation, and are provided with vertical openings 8—12, in order to permit air to circulate between and through the sections. The sections are secured in assembled relation by tie rods 13 and 14.

The sections 1, 2, 4 and 5 are similar, and each of these sections is provided, as best shown in Figure 2, with a water chamber 15, a combustion chamber 16 and a flue 17. The combustion chamber 16 is located immediately below the water chamber 15, and the horizontal dimensions thereof are similar to the corresponding dimensions of the water chamber 15. The flue 17 is of circuitous formation, and has vertical passages 18—21 located wholly within the water chamber 15.

The flue 17 has an upper passage 22 connecting the upper ends of the passages 18 and 21 and located in the water chamber 15. The flue 17 has a lower passage 23 connecting the lower ends of the passages 19, 20 and 21 and located within the combustion chamber 16. The flue 17 has an upper passage 24 connecting the upper ends of the passages 19 and 20. The passage 18 communicates at its lower end, as at 25, with the combustion chamber 16 forwardly of the flue passage 23, and the upper ends of the passages 19

and 20 and the passage 24 communicate with a hollow boss 26 formed on the inner side of the radiator section. The lower end portions of the flue passages 18-21 are each spaced from one side wall and from the end walls of the water chamber 15 in order to permit the water to circulate around the same. The major portion of each of the flues from the upper end is of the same width as the unit in which it is formed, being cast with and between the side walls thereof. The openings 8 of the radiator section are located between the flue passages 18-21 so as to permit the heating of their walls by the products of combustion flowing through the flue 17 from the combustion chamber 6 to the hollow outlet bosses 26.

The central section 3 is somewhat similar to the other sections. As best shown in Figure 3, this section is provided with a water chamber 27, a combustion chamber 28, and a flue 29. The combustion chamber 28 is located immediately below the water chamber 27, and the horizontal dimensions thereof are similar to those of the water chamber. The flue 29 is of circuitous formation, and the vertical passages 30, 31 and 32 thereof are located wholly within the water chamber 27.

The passages 30 and 31 communicate at their upper ends, and the passages 31 and 32 communicate at their lower ends by way of a passage 33 located within the combustion chamber 28. The lower end of the passage 30 communicates, as at 34, with the combustion chamber 28 forwardly of the passage 33, and the upper end of the passage 32 communicates with an outlet orifice 35 at the rear side of the section 3 and adapted to be connected by a pipe, not shown, to a chimney. Two of the openings 10 of this section are located between the passages 30-32, and the remaining opening is located close to the passage 32 so as to permit the walls of the openings to be heated by the products of combustion passing through the flue 29. The lower portions of the passages 30-32 are spaced from the side and end walls of the water chamber 27 so as to permit the water to circulate around the same. This section is laterally enlarged, as shown at 36, in Figure 7, in order to permit the formation of the discharge opening 35 of a size large enough to carry the products of combustion to the chimney. The flues 17 of the sections 1, 2, 4 and 5 as well as the flue 29 of the section 3 communicate with the discharge opening 35, and the communication between the flues 17 and the discharge opening is established by the bosses 26 of the sections 1, 2, 4 and 5 and hollow bosses 37 formed on the section 3 and communicating with the discharge opening. The tie rod 14 passes through the bosses 26 and 37, and a spacing sleeve 38 surrounds this tie rod and passes through the bosses and contacts at its ends with the inner sides of the sections 1 and 5, the spacing sleeve being smaller than the bosses to permit the products of combustion to flow therethrough from the flues 17 to the discharge opening 35.

Air inlet openings 39 are formed in the upper end of the passage 32 of the flue 29, as shown in Figure 3, and air inlet openings 40 are formed in certain of the flue passages 23, as best shown in Figures 5 and 6, to insure a draft through the flues. Figure 7 more clearly shows the air inlet passages 39 which, as shown in Figure 3, enter into the discharge opening 35. The bottom walls, the end walls and certain of the side walls of the passages 23 of the flues 17 are spaced

from the corresponding walls of the combustion chambers 16, and the bottom wall, the end walls and one side wall of the passage 33 of the flue 29 are spaced from the corresponding walls of the combustion chamber 28, to the end that these 80 passages may be heated to a high degree.

A water tank 41 is carried by the section 3, and is provided with a central opening 42 with which the outlet opening 35 of this section communicates and which is adapted to receive one end of the pipe by which the outlet opening is to be connected to a chimney. The upper and lower ends of the tank 41 are in communication with the water chamber 27 of the section 3 by way of openings 43 and 44. The tank 41 is provided with a filler nipple 45 closed by a screw plug 46, and it is also provided with a water gauge 47. Hollow bosses 48 establish communication between the lower ends of the water chambers of the sections 1-5, and hollow bosses 49 establish communication between the upper ends of these chambers, the latter bosses being located below the normal water level of the chambers.

Burners 50 carried by a gas distributing pipe 51 are arranged in openings 52 formed in the bottom walls of the combustion chambers 16 and 28. The burners 50 are of elongated formation and extend longitudinally of the combustion chambers 16 and 28 with portions thereof located below the portions of the flue passages 23 and 33. The pipe 51 is supported by the feet 6 and 7 which are provided with openings 53 for the reception of the ends of the pipe. One end of the pipe 51 is closed, and the other end thereof is provided with an air regulator 54. A regulating mechanism 55 is secured, as at 55a, to the section 1. A gas supply pipe 56 equipped with a cut-off valve 56a discharges into the regulator 55, and a pipe 56b extends from the regulator to the burner pipe 51. The regulator 55 which is of well-known construction, communicates with the water chamber 15 of the section 1, and functions when the water is heated to a predetermined degree to cut-off the supply of 105 gas to the burner pipe 51 and also functions when the temperature of the water falls below such degree to admit gas to the burner pipe. The normal level of the water in the chambers 15 and 27 is at least one inch below the tops 110 of the chambers, and a safety valve 55b of well-known construction, which is carried by the central section 3, communicates with the water chamber 27 of this section at a point above such level. Hollow bosses 57 establish communication 115 between the combustion chambers 16 and 28 immediately above the burners 50. A tube 58 is carried by the outer side of the section 1 in alignment with the bosses 57, this tube and the bosses 57 permitting the burners 50 to be lit.

From the foregoing description, taken in connection with the accompanying drawings, it will be understood that, when the radiator is in use, the flames of the burners 50 will impinge against the bottom walls of the water chambers 15 and 27 and against the bottom and certain end and side walls of the flue passages 23 and 33, and that the products of combustion will flow in circuitous paths through the water chambers 15 and 27. Due thereto, as the water surrounds the lower end portions of the vertical passages of the flues 17 and 29, and as the products of combustion are heated after passing once through and before passing the second time through the water chambers 15 and 27, and also due to the fact that the 130

- walls of the air passages or openings 8—12 in the sections 1—5 are heated by the products of combustion, substantially all of the heat generated by the burners 50 will be utilized in warming the room in which the radiator is located, and a comparatively large amount of heat will be developed from the consumption of a comparatively small amount of fuel. 80
- If desired electric heaters may be substituted for the gas burners 50. Also steam instead of hot water may be employed as the heating medium. Provision is made for the use of a safety valve of a suitable type when steam is employed, and such valve will be engaged in the plugged opening 60 of the section 1. 85
- While I have described the principle of the invention, together with the structure which I now consider the preferred embodiment thereof, it is to be understood that the structure shown is merely illustrative and that such changes may be made, when desired, as fall within the scope of the invention as claimed. 90
- What is claimed is:—
1. A radiator comprising relatively flat columns arranged in side by side spaced relation and each having a water chamber, a combustion chamber located below the water chamber, and a flue communicating with the combustion chamber and extending in a circuitous path through the water chamber, one of the columns having a discharge opening adjacent its top and at one edge with which the flues communicate, and heat generators located in the combustion chambers. 100
  2. A radiator comprising relatively spaced columns each having a water chamber, a combustion chamber located below the water chamber, and a flue communicating with the combustion chamber and extending in a circuitous path through the water chamber and having a part thereof located in the combustion chamber, one of the columns having a discharge opening with which the flues communicate, and heat generators located in the combustion chambers. 110
  3. A radiator comprising relatively spaced columns each having a water chamber, a combustion chamber located below the water chamber and having horizontal dimensions similar to those of the water chamber, and a flue communicating with the combustion chamber and extending in a circuitous path through the water chamber and having a part thereof located within the combustion chamber, one of the columns having a discharge opening with which the flues communicate, and heat generators located in the combustion chambers. 120
  4. A radiator comprising relatively spaced columns each having a water chamber, a combustion chamber located below the water chamber and having horizontal dimensions similar to those of the water chamber, and a flue communicating with the combustion chamber and extending in a circuitous path through the water chamber and having a part thereof located within the combustion chamber, parts of those portions of the flues located in the water chambers being spaced from the walls of such chambers and those parts of the flues located in the combustion chambers being spaced from certain walls of such chambers, one of the columns having a discharge opening with which the flues communicate, and heat generators located in the combustion chambers. 130
  5. A radiator comprising relatively spaced columns each having a water chamber, a combustion chamber located below the water chamber, and a flue communicating with the combustion chamber, one of the columns having a discharge opening with which the flues communicate, such column having air inlet openings for the flue thereof located near said discharge opening, and certain of the other columns having air inlet openings for the flues thereof and located near the inlet ends of the flues, and heat generators located in the combustion chambers. 140
  6. A radiator comprising relatively spaced columns each having a water chamber, a combustion chamber located below the water chamber, and a flue communicating with the combustion chamber and extending through the water chamber, one of the columns having a discharge opening with which the flue thereof communicates, means establishing communication between said last named flue and the flues of the other columns, means establishing communication between the water chambers of the respective columns, a water tank secured to the column having the discharge opening and communicating near its upper and lower ends with the water chamber of such column, and heat generators located in the combustion chambers. 150
  7. A radiator comprising relatively spaced columns each having a water chamber, a combustion chamber located below the water chamber, and a flue communicating with the combustion chamber and extending through the water chamber, one of the columns having a discharge opening with which the flue thereof communicates, means establishing communication between said last named flue and the flues of the other columns, means establishing communication between the water chambers of the respective columns, a water tank carried by the column having the discharge opening and communicating at its upper and lower ends with the water chamber of such column, the tank having an opening extending therethrough with which said outlet opening communicates, a filler tube carried by the tank, and a water gauge carried by the tank. 160
  8. A radiator comprising relatively spaced columns each having a water chamber, a combustion chamber located below the water chamber, and a flue communicating with the combustion chamber and formed to provide a series of passages circuitously extending through the water chamber, and one of the columns having a discharge opening with which the flues communicate, the columns being provided with air openings located between the passages of the flues, and heat generators located in the combustion chambers. 170
  9. A radiator comprising relatively spaced columns each having a water chamber, a combustion chamber located below the water chamber, and a flue communicating with the combustion chamber and extending through the water chamber, one of the columns having a discharge opening with which the flues communicate, the combustion chambers being provided in their lower sides with openings, burners arranged within the openings, a distributing pipe carrying the burners, means for supporting the radiator and the distributing pipe, means establishing communication between the combustion chambers at points above the burners, and one of the columns being provided with a lighting opening located in alignment with said last means. 180
  10. A radiator comprising a series of flat columns arranged in spaced side by side relation and interiorly formed to provide a water chamber and

- a combustion chamber at the bottom of the column, means for establishing communication between the water chambers of the columns, means for establishing communication between the combustion chambers of the columns, an end one of the columns having its combustion chamber open to the atmosphere, a flue within the water chamber of each column having a series of connected vertical passages forming a continuous tortuous 10 passage, one of said vertical passages at one end of the tortuous passage opening at its lower end into the combustion chamber of the column, means for coupling the other ends of the tortuous passages of the columns together adjacent 15 the top of the columns, means forming an outlet to the atmosphere for the other end of the tortuous passage of one of the columns, the said flue of each column being cast between the side walls of the column and adjacent the bottom of said 20 column being reduced in width and being in spaced relation with the opposite side wall thereof, and heating means in the combustion chambers of the columns.
11. A radiator, comprising a series of relatively 25 flat hollow columns arranged in spaced side by

side relation, partitioning means in the lower part of each of said columns dividing the same into a combustion chamber at the bottom and a water chamber thereabove, a flue passage in each column comprising a body cast integral with the side 80 walls of the column and adjacent the bottom of the column being reduced in width and being spaced from the opposite side wall, the flue being formed to provide a tortuous passage one end of which opens into the combustion chamber of the column, the other end of each tortuous passage communicating with an opening in the side wall of the column adjacent the top of the latter, the last mentioned openings of the columns being connected together, a central one of said columns having an outlet from the said other end of its tortuous passage to the atmosphere and comprising a cylindrical body communicating with the tortuous passage and extending beyond one edge 85 of the column, the said cylindrical body forming a common outlet for all of the passages of the columns, air inlet means for said common outlet, and heating means in the combustion chamber 90 of each column.
